DEVICE FOR HANDLING ELECTRIC LAMPS AND THE LIKE

Filed June 21, 1922

Patented Dec. 11, 1923.

1,476,817

UNITED STATES PATENT OFFICE.

GEORGE E. HATFIELD, OF DAYTON, OHIO.

DEVICE FOR HANDLING ELECTRIC LAMPS AND THE LIKE.

Application filed June 21, 1922. Serial No. 570,643.

To all whom it may concern:

Be it known that I, GEORGE E. HATFIELD, a citizen of the United States, residing at Dayton, in the county of Montgomery and State of Ohio, have invented certain new and useful Improvements in Devices for Handling Electric Lamps and the like, of which the following is a specification, reference being had therein to the accompanying drawing.

This invention relates to a device for handling electric lamps and the like.

In places such as theaters where colored lamps are used in considerable quantities it is necessary to wash and recolor the lamps at more or less frequent intervals. The lamps are usually washed, that is, the old color removed, by dipping them in lye water, rinsing them in hot water, and then dropping them on a bed of sawdust or similar material to dry.

One object of the present invention is to provide a device by means of which the lamp may be manipulated during this washing process without the hands of the operator coming in contact either with the washing solution or with the lamp; or which may be used for temporarily supporting electric lamps or similar devices where no current is required.

Another object of the invention is to provide such a device with means for supporting the same on a receptacle with the lamp immersed, or partly immersed, in the solution within the receptacle.

A further object of the invention is to provide a device of this kind which will be simple in its construction and which may be quickly and easily operated to insert and remove the lamp and which can be produced and sold at a low cost.

Other objects of the invention may appear as the device is described in detail.

In the accompanying drawings Fig. 1 is a side elevation of a device embodying my invention, showing the lamp supported within a receptacle; Fig. 2 is a front end elevation of the same; Fig. 3 is a longitudinal sectional view showing the device without the supporting clamp; and Fig. 4 is a top plan view of one end of the device.

In these drawings I have illustrated one embodiment of my invention and have shown the same as comprising a handle upon which is mounted a two part socket,

one part of which is movable relatively to the other to permit the base of the lamp to be inserted in and removed from the socket and which is provided with means for holding the movable portion of the socket in its operative position, that is, in a position to clamp the base of the lamp between the two parts of the socket. It will be understood that the particular device here shown has been chosen for the purposes of illustration only and that the invention may take various forms without departing from the spirit thereof.

The particular device here shown comprises a handle 1 which may be made of wood and on which is mounted the socket consisting of two parts, 2 and 3. The part 2 is in the present instance, rigidly secured to the end of the handle 1 and is here shown as having formed integral therewith a base 4 which is secured to the end of the handle 1 by means of a screw 5. The other part 3 of the socket may be mounted in any suitable manner for movement toward and from the part 2 of the socket. In the present form of the device the part 3 of the socket is carried by and preferably formed integral with a lever 6 extending lengthwise of the handle and pivotally mounted between its ends on a pivot pin 7 mounted in lugs 8 secured to the handle 1 and in the present instance formed integral with a plate 9 which may, if desired, be formed integral with the base 4 of the part 2 of the socket, thus enabling the part 2 of the socket, its base, the plate 9 and the lugs 8 to be cast as a unit. The movable part 3 of the socket is preferably held in its operative position by means of a spring and I have here shown a spring 10 coiled about the pivot pin 7 having one end bearing against the plate 9 and having the other end looped beneath that end of the lever opposite the part 3 of the socket. This end of the lever may be provided with a thumb piece 11 by means of which the lever may be moved against the action of the spring to operate the two parts of the socket, thereby permitting the base of the lamp to be inserted in the socket. When the lever is released the spring will move the part 3 of the socket toward the part 2 thereof, thus causing the base of the lamp to be clamped between the two parts of the socket. Preferably, both parts of the socket are pro-

vided with screw threads which are so arranged that when the two parts of a socket are in their closed position the threads thereof will engage the threads on the base 6 of the lamp and thus firmly hold the same against movement in the socket.

- It will be apparent from the foregoing description that the device is very simple in its construction and that it may be 10 easily operated by manipulating the lever 6 with the thumb of the hand which grasps the handle 1. While the lamp will usually be lifted by the hand of the operator and placed in the socket, this is not essential 15 as the base of the lamp can be gripped between the two parts of the socket while the lamp is lying on its side. The washing or other treatment of the lamp may then be accomplished and the lamp finally released 20 from the socket without the necessity of the operator touching the lamp with his hands. The device comprises but a few pieces, that is, the handle 1, the two parts of the socket with their connected devices, the pivot pin 25 7 and the spring 10. Not only can these parts be very cheaply manufactured but they are very easily assembled, thereby permitting the device to be produced at a very low cost.
- 30 Certain treatments of the lamps, such as etching, require that they be immersed, or partly immersed, in a solution and retained therein for a period of time. To enable the device to be utilized for this purpose I have provided the same with a supporting 35 clamp by means of which it may be secured to the edge of a pail, or other receptacle, and the lamp supported in the solution within the receptacle. As here shown, the supporting lamp comprises a bracket 12 having a two part socket 13 adapted to 40 embrace the handle 1 and to be clamped thereon by means of a screw 14. Secured to this bracket is a clamping device and in the present instance the bracket comprises 45 an upright portion, or plate, 15, the lower part of which constitutes one member of the clamp. Pivotaly mounted on the bracket is a lever 16, the lower end portion 50 of which constitutes the other member of the clamp. As here shown, the lever 16 is pivotaly mounted between its ends on a pin 17 mounted in pivot lugs 18 carried by the upright member 15 of the bracket. The 55 upper portion of the lever extends above the bracket and is provided with a thumb piece 19 by means of which the clamp may be manipulated. A spring acts on the lever to move the lower end thereof toward the 60 fixed clamping member 15. In the present

device the spring is shown at 20 as coiled about the pin 17 and having its ends bearing respectively against the upright member 15 of the bracket, and the upper portion of the lever 16. The lower portion of the 65 movable member is provided with a clamping head 21 which is curved to conform it to curvature of the pail and is preferably inclined to accommodate it to the inclination of the wall of a tapered pail. In order 70 that the device may be mounted on a receptacle, or pail, having a vertical wall and the lamp supported in an upright position therein, I have mounted in the lower portion of the lever 16 an adjustable stop, such as a 75 screw 22 which may be so adjusted that it will engage the outer surface of the receptacle at the same time that the ends of the curved head 21 engage the pail, thus retaining the handle 1 in a vertical position. It will be understood that the lamp 80 handling device may be used either with or without the supporting clamp, but by the use of the clamp the device is given a much wider range of utility.

85 While I have shown and described one embodiment of my invention I wish it to be understood that I do not desire to be limited to the details thereof as various modifications may occur to a person skilled in the 90 art.

Having now fully described my invention what I claim as new and desire to secure by Letters Patent is:

1. In a device of the character described, 95 a handle, a two part socket carried by said handle, and adapted to receive the base of an electric lamp, one part of said socket being movable toward and from the other part thereof, and means for retaining the 100 movable part of said socket in its operative position.

2. In a device of the character described, 105 a handle, a two part socket carried by said handle, and adapted to receive the base of an electric lamp, one part of said socket being movable toward and from the other part thereof, and a spring acting on the movable part of said socket to yieldingly hold the same in its operative position.

3. In a device of the character described, 110 a handle, a two part socket carried by said handle, and adapted to receive the base of an electric lamp, means for pivotaly mounting one part of said socket on the handle for movement toward and from the other part of said socket, and means for holding said movable part of said socket in operative relation to said other part of said socket.

4. In a device of the character described, a handle, a two part socket carried by said handle and adapted to receive the base of an electric lamp, one part of said socket being movable toward and from the other part thereof, a lever pivotally mounted on said handle and supporting the movable part of said socket, and means for holding said movable part of said socket in its operative position. 5. In a device of the character described, a handle, a two part socket carried by said handle and adapted to receive the base of an electric lamp, one part of said socket being movable toward and from the other part thereof, a lever pivotally mounted on said handle and supporting the movable part of said socket, and means acting on said lever to hold the movable part of said socket in its operative position. 10. In a device of the character described, a handle, a two part socket carried by said handle and adapted to receive the base of an electric lamp, one part of said socket being movable toward and from the other part thereof, means for retaining the movable part of said socket in its operative position, and a supporting device connected with said handle and having means for gripping the edge of a receptacle. 15. In a device of the character described, a handle, a two part socket carried by said handle and adapted to receive the base of an electric lamp, one part of said socket being movable toward and from the other part thereof, a lever pivotally mounted on said handle and supporting the movable part of said socket, and means acting on said lever to hold the movable part of said socket in its operative position. 20. In a device of the character described, a handle, a two part socket carried by said handle and adapted to receive the base of an electric lamp, one part of said socket being movable toward and from the other part thereof, a lever pivotally mounted on said handle and supporting the movable part of said socket, a spring acting on said lever to hold said movable part of said socket in its operative position, and means for actuating said lever against the tension of said spring. 25. In a device of the character described, a handle, a two part socket carried by said handle and having screw threads to receive the screw threaded base of an electric lamp, said socket being divided near the longitudinal center thereof, and one part thereof being movable toward and from the other part thereof, a spring to retain the movable part of said socket normally in its operative position, and means operable by the hand which grasps the handle to move said movable part of said socket into an inoperative position. 30. In a device of the character described, a handle, a two part socket, one part of said socket having a base adapted to be rigidly secured to said handle, a lever pivotally mounted on said handle and carrying the other part of said socket, and a spring acting on said lever to move said movable part of said socket toward the other part thereof. 35. In a device of the character described, a handle, a two part socket, one part of said socket having a base extending transversely thereto and adapted to be rigidly secured to the end of said handle, a plate connected with said base and secured to the side of said handle, pivot lugs carried by said plate, a lever pivotally mounted between its ends on said pivot lugs and carrying the other part of said socket, a spring acting on said lever to move the last mentioned part of said socket toward the first mentioned part thereof, and means for manipulating said lever against the action of said spring. 40. In a device of the character described, a handle, a two part socket carried by said handle and adapted to receive the base of an electric lamp, one part of said socket being movable toward and from the other part thereof, means for retaining the movable part of said socket in its operative position, and a supporting device adjustably mounted on said handle and having means for gripping the edge of the receptacle. 45. In a device of the character described, a handle, a two part socket carried by said handle and adapted to receive the base of an electric lamp, one part of said socket being movable toward and from the other part thereof, means for retaining the movable part of said socket in its operative position, and a supporting device mounted on said handle and comprising clamping members, one of which is yieldably mounted with relation to the other. 50. In a device of the character described, a handle, a socket carried by said handle to receive the base of an electric lamp, a supporting device having means for detachably securing the same to said handle, and comprising two members, one of which is movable toward and from the other, said members being adapted to clamp the edge of the receptacle between them. 55. In a device of the character described, a handle, a socket carried by said handle and adapted to receive the base of an electric lamp, a bracket having means for securing the same to said handle, a fixed clamping member carried by said bracket, a movable clamping member carried by said bracket, and a spring acting on said movable clamping member. 60. In a device of the character described, a handle, a socket carried by said handle and adapted to receive the base of an electric lamp, a bracket having means for securing the same to said handle, a fixed clamping member carried by said bracket, and a movable clamping member carried by said bracket, and a spring acting on said movable clamping member.

member carried by said bracket, a movable clamping member carried by said bracket, a spring acting on said movable clamping member, said movable clamping member having an inclined clamping head to accommodate the same to the inclined wall of a receptacle.

16. In a device of the character described, a handle, a socket carried by said handle and adapted to receive the base of an electric lamp, a bracket having means for securing the same to said handle, a fixed clamping member carried by said bracket, a movable

clamping member carried by said bracket, a spring acting on said movable clamping member, said movable clamping member having an inclined clamping head to accommodate the same to the inclined wall of a receptacle, and an adjustable stop carried by said movable clamping member and adapted to engage the wall of the receptacle above said head.

In testimony whereof I affix my signature hereto.

GEORGE E. HATFIELD.
